INTERCHANGEABLE HAT CONSTRUCTION

Abraham I. Josephs, New York, N. Y.

Application October 11, 1943, Serial No. 505,714

5 Claims. (Cl. 2—195)

1

This invention relates generally to headgear and more particularly to interchangeable hat or cap construction.

In connection with certain forms of headgear particularly for naval or military use it is desirable to use a standard frame with replaceable crowns or covers. This reduces the officer's or wearer's burden in that he need carry with him on his travels only a single frame and a plurality of separate relatively easily packed covers or crown portions. In connection with naval officer's use at the present time it is customary to require one dark blue crown, two white crowns and possibly a khaki crown.

In accordance with the present invention a single frame of a partially collapsible nature is used in cooperation with a series of different crowns, and it is among the objects of the invention to provide such structure which shall be relatively flexible and light in weight so as to be easily carried and so as to be comfortable when worn.

Since it is desirable that the wearer may be able to wash the light colored or khaki crowns wherever he may be, it is another object of the present invention to provide hat structure in which the crown may be removed from the frame for washing or cleaning and the stretcher ring may also be removed from the frame to be used in connection with the proper shaping of the crown as it dries after washing or cleaning.

A still further object lies in the provision of an interchangeable type of hat or cap in which the stretcher ring may be removed for a soft appearance or for increased comfort and adaptability when a telephone receiver headset is worn right over the cap.

Another object of the present invention lies in the provision of a hat or cap of the class described in which the insertion or installation of the crown stretcher ring into the crown of the hat or its removal therefrom is facilitated, so as to become an easily, quickly and conveniently performed operation requiring no tools or special skill.

A further object of the invention lies in the provision of structure having the above described interchangeable crown features yet which is of light weight and is durable so that a flexible peak or visor construction may be utilized.

A still further object lies in the provision of combination sweatproofing and identification means which is connected to the cap frame and is thus usable with any one of a series of separate crowns, thereby reducing the number of parts

2

and printing operations with a consequent reduction in cost of materials and manufacture.

Another object lies in the provision of means for properly initially placing a crown upon the frame so that the remaining crown attaching operations are made more convenient and quickly performed.

Another object lies in the provision of structure means for adjusting the position of a portion of the combination sweatproof and identification means so that the said means may take a balanced position in the cap for purposes of comfort and appearance and ease of manufacture.

These objects and other incidental ends and advantages will more fully appear in the progress of this disclosure and be pointed out in the appended claims.

In the accompanying drawings, in which similar reference characters designate corresponding parts throughout the several views:

Figure 1 is a bottom plan view of a naval officer's cap as an illustrative embodiment of the invention.

Figure 2 is a side elevational view of the cap shown in Figure 1.

Figure 3 is a fragmentary elevational view showing the rear or inner portion of the front support element and some of the associated structure as the same might be seen from inside the cap looking forward.

Figure 4 is an enlarged vertical longitudinal sectional view as seen from the plane 4—4 on Figure 1.

Figure 5 is a reduced bottom plan view showing the crown removed from the frame.

Figure 6 is a reduced plan view of the crown stretcher ring.

Figure 7 is a fragmentary rear elevational view of the cap or hat frame with the crown and decorative band removed showing the means for adjustably connecting the rear portion of the sweatproof and identification means to the main band.

Figure 8 is an enlarged fragmentary sectional view as seen from the plane 8—8 on Figure 2.

In accordance with the invention, the hat or cap generally indicated by reference character 10 comprises broadly a frame 11, a crown 12, a stretcher ring 13, and connector means 14, 15, and 16 (see Figures 1 to 8 inclusive).

The frame 11 is of generally circular configuration of a size and shape adapted to fit the head of the wearer and may include a main band 17, an auxiliary band 18, a sweatband 19, a decorative outer band 20, a reinforcing strip 21, a

frontal support 22, stretcher ring detachably engaging means 23, and a decorative strap 24. Integrated with the frame 11 is the peak or visor 25.

The crown 12 is of generally circular configuration of a size and shape to conform or correspond with the size and shape of the frame 11 from both utilitarian and aesthetic considerations and may include a top wall 26, a front wall 27, rear quarter walls 28 and 29, a retainer band 30, and a sweatproof and identification means carrier 31. While only one crown 12 is shown in the drawings, as will more fully appear as this disclosure proceeds, any desired number of other crowns, having different color or fabric characteristics but otherwise of substantially identical construction may be substituted therefor.

The main band 17 is of annular shape and may be made of any suitable material having the desired stiffness with some flexibility. Covered buckram, or straw or fiber webbing may be used. Additional strength and shape holding properties may be obtained by the use of spiral stitching (not shown) well known in this art.

Secured about the lower horizontal edge of the main band 17 in any suitable manner, as for example by the row of stitches 32 is the auxiliary band 18 having a cushioning inner portion 33 and an outer portion 34. Thus, as best seen in the sectional views in Figures 4 and 8 the auxiliary band 18 is U shape in cross section with the outer leg (the outer portion 34) being taller. The outer portion 34 rearwardly of the visor 25 is provided with an outwardly extending flange, bead or rib 35 which is peripherally disposed. The rib 35 furnishes vertical support to the lower edges of the retainer band 30 and the decorative band 20 thereabove. In the area above the visor 25 some vertical support is given to the lower edges of the retainer band 30 and the decorative band 20 by the upper portion of the visor.

The auxiliary band 18 is preferably composed of soft felt or heavy loosely woven flannel. The upper edge of the outer portion 34 may be further secured in place by the row of stitches 36 joining said portion to the main band 17. The rib 35 may be formed by sharply bending or folding the lower part of said outer portion 34 and securing the bend or fold so formed by a row of stitches 37 (see Figure 8).

The sweat band 19 may be of the usual type, an annular band of leather or other absorbent material and is secured at the lower edge 38 thereof to the inner portion of the bottom fold of the auxiliary band 18, by a row of stitches 39. The sweat band 19 not only performs its ordinary function, but also protects the head of the wearer from contacting the nuts on the inner ends of the connector means 14, 15, and the prongs forming the inner ends of the connector 16.

Disposed forwardly of the main band 17 above the upper edge of the outer band portion 34 and secured to the upper portion of said band in any suitable manner as for example by means of the hollow rivets 40 and 41 is the frontal support member. This support member 22 is preferably composed of relatively stiff but flexible material and while shown as being of a single layer of planar material, it may be laminated. The frontal support member 22 has a first portion which is secured to the upper portion of the band 17 by the rivets 40 and 41 and which is relatively stationary, while the second or remaining portion of the frontal support member is arcuately movable with respect to the first portion. (See the dot-dash lines in Figure 4.) As seen in the

full lines in said figure the second portion of the frontal support member is maintained in proper operative position by the ring 13 as will more fully appear hereinbelow. Furthermore the frontal support member may be provided with additional stays or stiffeners (not shown). The upper edge 42 of the member 22 is curved to conform to the shape of the juncture 44 of the top wall 26 and the front and rear walls 27-29 when the parts are in engaged position or fully set up. The edge 42 may be bound with tape 43.

The frontal support member 22 at the upper edge 42, centrally thereof, is provided with the stretcher ring detachably engaging means 23 which takes the form of a pocket or recess. This pocket or recess is formed by the connection of the upper edge 42 to the forward edge 72 of the carrier 31.

Forwardly of the lowermost portion of the frontal support member 22 and the portion 34 of the auxiliary band 18 thereat is the reinforcing strip 21 which is suitably connected to the main band 17, for example by the rivets 45 and 46.

The decorative outer band 20 is an annular band and may be composed of any suitable decorative material, for example, it may be composed of flat braid. The decorative strap 24 may be made of leather, metallic braid or webbing. The band 17, the band 20 and the strap 24 are provided with orifices positioned to coincide with the position of the connector means 14 and 15 when said bands and strap are in proper place upon the cap 10. In the case of the band 20 these orifices are substantially diametrically disposed in the opposed side portions thereof while in the strap they are located substantially at the terminals thereof.

The crown is preferably composed of a suitable planar material such as woven cloth and the top wall may be secured to the inwardly and downwardly converging front wall 27 and rear quarter walls 28 and 29 by suitable stitching along the juncture 44. The side edges of the front wall 27 and the rear quarter walls 28 and 29 are interconnected along the seams 47, 48, and 49, while the lower edges of these walls are connected by an annular row of stitches 50 to the upper edge of the retainer band 30. While not shown for the purpose of clarity in the drawings, exposed edge seams may be taped in a well known manner, and the lower edge of the band 30 may have a double hem to slightly stiffen and reinforce the same. The band 30 is provided with two substantially diametrically disposed orifices in the opposed side portions thereof, and with another orifice in the upper central front portion thereof all to coincide with correspondingly positioned orifices in the band 20 to permit penetration thereof by the connectors 14, 15 and 16.

Directly below the inner surface of the top wall 26 and preferably arranged longitudinally of the cap 10, the sweatproof and identification means carrier 31 is secured at the forward end thereof to the edge 42 of the support 22 as has been previously described, and at the rear end thereof to the slide member 16. The carrier 31 is preferably in the form of a piece of waterproof cloth and has spaced and parallel longitudinal edges which converge toward the rear.

The sweatproof and identification means carrier 31 includes a base plate portion 54 and a transparent plate 55 which is secured to the portion 54 along the substantially rectilinear rows of stitching 56 to 61 inclusive. The base plate portion 54 within the area defined by the stitches

56, 57, 59 and 60 may have imprinted thereon any suitable indicia 62 which may take the form of a trade-mark which is thus protected by the transparent plate thereover. The transparent plate 55 within the area defined by the stitches 57, 58 and 61 forms a pocket 64 within which may be removably inserted the identification card 63 which may carry the owner's name and/or number. The card 63 is frictionally retained in the pocket 64.

The connector means 14 and 15 may be formed of screw stems with a head on the outer end and a sleeve nut on the inner end of each. The heads on the means 14 and 15 may be in the form of decorative buttons carrying insignia thereon. The connector means 16 may be in the form of a well known two legged brass paper fastener with the head thereof positioned forwardly of the strip 21 and spread leg ends thereof disposed rearwardly of the main band 17. The main band 17 and the auxiliary band 18 are provided with oppositely disposed orifices to permit passage therethrough of the central portions of the connector means 14 and 15; while the main band 17 and the reinforcing strip are provided with aligned orifices to permit passage of the central portion of the connector means 16. The portion 34 is also orificed for the connector 16.

The crown stretcher ring 13 is an annular device preferably composed of metal or plastic. It may be composed of flat strip spring steel, and this may be covered for protection and appearance. Its effective diameter is such that when it is in position in the larger top portion of the crown and the carrier 31 it exerts a constant radially outward pressure.

The removal, cleaning, and replacement of the crown 12 is a relatively quick and easy matter. One method, by way of illustration is here given: Assuming the cap 10 to be fully assembled as shown in Figures 1, 2, 4, and 8, to remove the crown 12, first the ring 13 is manually undulated to temporarily reduce its effective diameter and it is snapped out of the cap 10 by pulling it downwardly as viewed in Figure 4, out of engagement with the means 23. The crown now becomes limp. The sweat band is now pulled down through 180° and the nuts on the connector means 14 and 15 are removed. The connector 16 is removed by bending the ends of the legs into a parallel condition and pulling the head forwardly. Next the means 14, 15, and 16 are pulled out clear of the cap 10. The retainer band 30 now being only lightly frictionally engaged between the main band 17, the outer portion 34 and the strip 21 on one side and the outer band 20 on the other, is easily pulled away from the frame 11. The crown may now be laundered and may have the ring 13 inserted therein to shape it while drying.

After drying, the ring 13 is removed and the crown 12 is replaced to its original position on the frame. The retainer band 30 is either tucked in, inwardly of the decorative outer band 20 or the band 20 may be removed and then replaced. The various orifices in the parts are now adjusted for realignment to their original positions and the connector means 14, 15, and 16 are replaced. In replacing the crown 12, this operation is facilitated by aligning the front part of the retainer band 30 and first inserting the connector 16, then the alignment of the orifices in the band 30 for the insertion of the connectors 14 and 15 will take place more or less automatically. Lastly the ring 13 is corrugated between the user's fingers, engaged with the means 23 and snapped into place

against the rear portion of the carrier 31 rearwardly of the plate 55 and substantially along the inner surface of the crown at the juncture 44. The ring 13 not only keeps the top wall 26 and the carrier 31 taut but also maintains the frontal support 22 in its proper angularly elevated position, thereby keeping the front wall 27 and the rear quarter walls 28 and 29 taut.

It may thus be seen that I have provided a novel and highly versatile hat or cap construction. Only a single means 53 need be used to protect and identify a plurality of crowns and this sweat-proof and identification means is permanently connected to the frame 11. Only a single trademark printing need be used with consequent reduced expense. The interbracing of the various parts permits them to be made of light weight comfortable materials without loss of durability and neat appearance. By virtue of the construction which I have outlined, when it is desired to compactly stow the frame, the frontal support member and the carrier 31 may be bent down to a position within the sweat band, that is within the annulus thereof, as indicated by the dot-dash lines in Figure 4. When the cap frame is subsequently set up, the ring 13 properly places and positions the support member 22 and the other parts as well.

Thus the frontal member 22 and the carrier 31, when the hat is collapsed for stowing or shipping, may take the position indicated by the dot-dash lines on Figure 4.

The carrier 31 is connected at the forward edge 12 thereof to the upper edge 42 of the frontal support element 22 to form a rearwardly opening pocket or means 23 for detachably engaging the stretcher ring 13. While the carrier 31 may be made of waterproof material such as cellulose acetate coated fabric, and thus act to prevent moisture from the head of the wearer from reaching the top wall 26, the plate 55 which may be made from cellulose acetate sheet, acts as an additional perspiration isolating medium. The rear terminal of the carrier 31 is folded upon and secured to itself in any suitable manner, as for example by means of the stitches 73 to form the transverse channel 74 which is slidably mounted on the slide member 76. The slide member 76 is secured to the outer rear surface of the main band 17 by means of the rivets 75 and 77 which penetrate the ends of the member 76 to leave a free portion of substantially greater length than the length of the channel 74.

By virtue of the construction just described the rear portion of the carrier 31 and hence the plate 55 may be shifted laterally of the hat or cap 10 to properly center the same for the purpose of comfort and appearance. Thus the connection of the rear portion of the carrier 31 with the frame 11 is an adjustable one and the operator in fabricating the hat or cap 10 need not take any time consuming care in locating the parts, since proper centering can be accomplished at a later time. This shiftability of the carrier 31 also permits the carrier to properly nest within the crown 12.

I wish it to be understood that I do not desire to be limited to the exact details of construction shown and described, for obvious modifications will occur to a person skilled in the art.

70 I claim:

1. An interchangeable crown hat construction comprising: a main band of annular form; a frontal support element connected to the main band, said frontal support element having front and rear surfaces and an upper edge; sweatproof-

ing means connected at the forward end thereof to the upper edge of the frontal support element forming therewith a rearwardly opening pocket and connected at the rear end thereof to the rear portion of the main band; a crown detachably engageable with said band and adapted to be disposed outwardly and above the sweatproofing means; a resilient stretcher ring detachably disposed between opposed portions of the sweatproofing means and engageable at the forward portion of said ring within said pocket.

2. An interchangeable crown hat construction comprising: a main band of annular form; a frontal support element connected to the main band, said frontal support element having front and rear surfaces and an upper edge; sweatproofing means connected at the forward end thereof to the upper edge of the frontal support element forming therewith a rearwardly opening pocket, and laterally shiftably connected at the rear end thereof to the rear portion of the main band; a crown detachably engageable with said band and adapted to be disposed outwardly and above the sweatproofing means; a resilient stretcher ring detachably disposed between opposed portions of the sweatproofing means and engageable at the forward portion of said ring within said pocket.

3. An interchangeable crown cap construction comprising: a frame; a frontal support, the lower portion of which is connected to the front portion of said frame; a flexible carrier connected at the rear thereof to said frame and at the front thereof to the upper edge of the frontal support; a crown detachably engageable with said frame; a stretcher ring detachably engageable with said flexible carrier and frontal support; said crown in the engaged position thereof superposing said frontal support, flexible carrier, and said ring.

4. An interchangeable crown hat construction comprising: an annular main band; a crown hav-

ing an enlarged top portion and detachably connected with said band; a carrier insertable into said enlarged top portion of the crown; means connecting said carrier with said band; a pocket associated with said carrier; identification means adapted to be inserted into said pocket; and a stretcher ring insertable between and engageable with opposed portions of the carrier in the enlarged top portion of the crown.

- 10 5. An interchangeable crown hat construction comprising: a main band; a support element having first and second portions, said first portion being attached to said band and said second portion being movable with respect to said first portion; 15 a carrier connecting the second portion of said support element and another portion of the band; a crown detachably connectable to said band; a stretcher ring disposed between the upper rear portion of said carrier and the forward portion of the carrier where it joins the second portion of the support element, said crown superposing the ring and carrier; and transparent pocket means associated with the carrier on the lower surface thereof for supporting identification means.
